GRATE CONSTRUCTION

Lafayette E. Safford, Cleveland, Ohio, assignor to
 Monroe Steel Castings Company, Detroit, Mich.,
 a corporation of Michigan

Application March 28, 1932, Serial No. 601,547

2 Claims. (Cl. 126—163)

My invention relates to grates and has particular reference to an improved type of grate structure admirably suited for use in conjunction with railroad locomotive boilers.

An object of the invention is to so arrange the grate bar assembly that the velocity of the air coming up through the bars will never be sufficient to disturb the fire bed. The induced draft type of furnace is utilized in locomotives and there are times, as when the drive wheels slip while gathering momentum, when a very high vacuum is produced above the fire bed by the rapid exhaust of the engine. This produces a rapid rush of air under atmospheric pressure into the ash pit and up through the grate and fire bed. The force of such a rush of air is often sufficient to blow large holes in the fire bed.

A further object of the invention is to secure more effective air distribution over the entire surface of the grate and provide more efficient air cooling of the grate by eddying the air currents for a sufficient space of time and over a sufficient distance to absorb a substantial amount of heat during its passage to the fire bed or top of the grate. In this way the temperature of the air is raised to more nearly that required for combustion purposes and more efficient operation is secured.

Yet another object of the invention is to provide a grate structure characterized by the above defined advantageous features and at the same time so construct it that it is light in weight and of sufficiently rigid construction to eliminate the possibility of warping or sagging when subjected to the high temperature and substantial weight of the fire bed.

Various other meritorious features of the invention will be found in the particular arrangement of parts illustrated in the accompanying drawing wherein like numerals refer to like parts throughout the several figures and wherein:

Fig. 1 is a front elevation, partly in section,

Fig. 2 is a top plan view, partly broken away and in section,

Fig. 3 illustrates the improved arrangement of grate bars, and

Fig. 4 is a vertical section through the center portion of Fig. 1, and

Fig. 5 illustrates a modified form of bar, in section.

Referring now to the drawing, the numeral 10 indicates the ash pit of the fire box. A double row of grate units 14 are positioned as indicated in Figs. 1 and 2 between the respective outside water-legs 11 and a central supporting member 12 ex-

tending between the rows. Each of the units embodies a substantially flat upper surface with the exception of the raised portions at each end forming the upper part of the supporting sockets 16 and 18 which are adapted to cooperate with the projecting lugs 20 and 22. The supporting sockets 16 and 18 are positioned at the extremities of the axis of each of the grate assemblies and each of the grates is adapted to rock about these supports for the purpose of dumping the ashes. 60

The improved grate construction comprises a pair of superposed rows of grate bars, the upper row being composed of bar formations 24 and the lower row being composed of the bar formations 26. While the gist of this invention does not include the particular manner in which the grate construction is manufactured, it has been found preferable to cast each assembly 14 as a unit. Under these circumstances the structure may be regarded either as involving a pair of superposed rows of bars or as embodying two spaced apart layers of substantial thickness having transverse slots 28 and 30 located in the layers respectively. 70

Where an integral casting is provided a plurality of ribs extend in parallel relation along the length of each assembly intermediate the upper and lower bar assemblies or layers for the purpose of providing the necessary strength and rigidity to the structure. These ribs are clearly indicated in Figs. 2 and 4 at 32 and 34 and constitute an 85 effective heat transfer medium to assist in more rapidly cooling the units. A central rib 36 extends downwardly, gradually increasing in depth toward the middle of the assembly as clearly illustrated in Fig. 1, for the purpose of further increasing the rigidity of the assembly as a whole and more rapidly dissipating the heat from the grate unit. 90

The outer extremities of the upper layer are turned over as indicated at 38 and join the outer 95 extremities of the lower layer to further assist in rigidifying the integral structure and cooling the same.

Depending from the longitudinal axis of each of the grate units 14 is an arm 40 provided with a 100 projecting pin 42 and each row of these projecting pins is coupled with a bar 44 extending the length of the row transversely of the grate units whereby all of the grate units in a row may be rocked simultaneously from one extremity of the 105 fire box.

Referring now to the improved construction more clearly illustrated in Fig. 3 of the drawing, it is to be noted that the bars 24 and 26 are so arranged that the upper bars are staggered in 110

relation to the lower bars, and that the upper surface of each lower bar 26 extends beyond the slot 28 between the upper bars 24 and lies in superposed relation to these bars along its outer side edges. The lower bars 26 are rounded as indicated at 48 at their lower extremities. The sides extend upwardly in diverging relation and are bevelled outwardly as at 50 adjacent their upper extremity.

10 The lower portion of each side edge of the upper bars 24 is chamfered as indicated at 52 and it will be noted that if the chamfered portion were continued on in its straight line direction downwardly it would substantially intersect the upper-side edges respectively of the lower bars 26.

15 The grate structure defined above provides what may be regarded as narrow cross slots directly over the web section below for the purpose of eddying the air currents as they travel upwardly from the ash pan 54 below. The passage of the air being so baffled, it is not only forced to travel over a longer path and therefore absorb a greater amount of heat whereby more efficient combustion is secured, but its velocity is cut down 20 so as not to disturb the fire bed on the grate. Furthermore, by virtue of the peculiar arrangement of the grate bar structures and their relationship to one another, the air currents coming up through the ash pan below are split whereby 25 the potential heat which the upwardly directed air is capable of absorbing is further increased. It will be noted that the lower web section comprising the bars 26 effectively baffles and divides the air, reducing the velocity and flow from below 30 by directing the air currents toward each other from opposite directions as they approach the slots 28 between the upper bars 24. It is this splitting of the air currents and the increase in their length of travel which facilitates the efficiency and maintains the uniformity of the fire 35 bed.

40 The double trussed design equalizes the load and permits a light rigid construction which will not warp or sag under the most severe service.

45 As indicated in Fig. 3 the spacing between the bars of the upper row may be less than that between the bars of the lower row, although the important point is to baffle the upper slot 28 by the lower bar 26. The velocity of the air is somewhat decreased as it reaches the top of the

5 grade by reason of the baffled passage thus provided.

While the structure has been illustrated as an integral casting, it will be apparent to those skilled in the art that the assembly could be 80 designed in such manner as to utilize a pair of units for the upper and lower assemblies without diminishing the advantages secured except the important matter of heat transfer from the upper to the lower bars.

85 A somewhat modified form of upper bar 25 has been illustrated in Fig. 5. The lower portion of each bar 25 in this upper row includes an arcuate recessed portion for the purpose of further assisting in creating eddy currents for cooling purposes. A circular or swirling motion of the air is brought about through this arcuate recess extending along the length of the bar on the lower side thereof which permits contact 90 between the bar and the air for a greater period of time.

95 While certain preferred modifications have been illustrated herein I wish to be limited only by the scope of the appended claims.

100 What I claim is:

1. A grate bar unit comprising an upper and lower series of transverse spaced parallel bars in overlapping staggered relation to one another, said bars being formed as an integral unit and merging into a continuous vertical flange 105 at each end, each flange being common to all the parallel bars, and a rigidifying and strengthening rib integral with said bars extending longitudinally between the same, the bottom face of each of the upper series of bars including a 110 recess extending the length thereof.

2. A grate bar unit comprising an upper and lower series of transverse spaced parallel bars in overlapping staggered relation to one another, said bars being formed as an integral unit and merging into a continuous vertical flange at 115 each end, each flange being common to all the parallel bars, and a rigidifying and strengthening rib integral with said bars extending longitudinally between the same, the bottom face of 120 each of the upper series of bars including a recess extending the length thereof, said recess being of a width approximately equal to the space between each of the lower series, and in substantial vertical alignment therewith.
